Application August 9, 1937, Serial No. 70,943

Term of patent 7 years

To all whom it may concern:

Be it known that I, Floyd V. Schleimer, a citizen of the United States and a resident of the city and county of San Francisco, State of California, have invented a new, original, and ornamental Design for a Combined Pedestal Head and Housing for Hair Waving Machines, of which the following is a specification, reference being had to the accompanying drawing, forming part thereof.

Referring to the drawing:

Fig. 1 is a top plan view of a combined pedestal head and housing for hair waving machines showing my new design.

Fig. 2 is a side elevational view.

Fig. 3 is a rear elevational view thereof.

I claim:

The ornamental design for a combined pedestal head and housing for hair waving machines, substantially as shown.

FLOYD V. SCHLEIMER.
